(57) **CLAIM**

The ornamental design for a draw latch, as shown and described.

DESCRIPTION

FIG. 1 is a top plan view of a draw latch showing our new design;

FIG. 2 is a perspective view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a top plan view of a second embodiment of a draw latch;

FIG. 7 is a perspective view of FIG. 6;

FIG. 8 is a front elevational view of FIG. 6;

FIG. 9 is a right side elevational view of FIG. 6, the left side elevational view being a mirror image thereof; and,

FIG. 10 is a rear elevational view thereof.

The broken lines are for illustrative purposes only and form no part of the claimed design.
